US00D618192S

(12) **United States Design Patent**
Huang et al.

(10) **Patent No.:** US D618,192 S
(45) **Date of Patent:** ** Jun. 22, 2010

(54) **VIDEO PANEL PHONE**

(75) Inventors: **Chien-Ju Huang**, Taipei Hsien (TW);
Chi-Hsiang Kao, Taipei Hsien (TW);
Yu-Wei Tu, Taipei Hsien (TW)

(73) Assignee: **Hon Hai Precision Industry Co., Ltd.**,
Tu-Cheng, Taipei Hsien (TW)

(**) Term: **14 Years**

(21) Appl. No.: **29/346,026**

(22) Filed: **Oct. 26, 2009**

(30) **Foreign Application Priority Data**

Sep. 11, 2009 (CN) 2009 3 0315485

(51) **LOC (9) Cl.** 14-03

(52) **U.S. Cl.** D14/130

(57) **CLAIM**

The ornamental design for a video panel phone, as shown and described.

DESCRIPTION

FIG. 1 is a perspective view of a video panel phone showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

In the drawing, the broken lines depict unclaimed environment.
